(57) **CLAIM**

The ornamental design for a key retaining pocket, as shown and described.

DESCRIPTION

FIG. 1 is a perspective view of a key retaining pocket showing my new design;

FIG. 2 is a front elevational view thereof, showing a key and key fob inserted into the key retaining pocket, which are shown in broken lines for illustrative purpose only and form no part of the claimed design;

FIG. 3 is a top plan view thereof;

FIG. 4 is a right side elevational view thereof, the left side view being a mirror image;

FIG. 5 is a rear elevational view thereof; and,

FIG. 6 is a bottom plan view thereof.
